MEYER AXILROD, OF READING, PENNSYLVANIA.

DRIVING MECHANISM FOR SEWING AND OTHER LIKE MACHINES.

1,320,194.

Specification of Letters Patent.

Patented Oct. 28, 1919.

Application filed October 30, 1918. Serial No. 260,258.

To all whom it may concern:

Be it known that I, MEYER AXILROD, a citizen of the United States, and a resident of Reading, in the county of Berks and State of Pennsylvania, have invented an Improvement in Driving Mechanism for Sewing and other like Machines, of which the following is a specification.

My invention relates to improvements in driving mechanism for driving and operating sewing machines and other like machines to which it is adapted.

The object of my invention is to simplify the construction of such devices by reducing the number of parts of which such mechanism is composed and by producing the same in a more compact form.

A further object of my invention is to eliminate gears and also to provide means whereby the speed of operation of the machine or machines operated and driven by the said mechanism may be readily varied and controlled.

Other objects and advantages of my invention will be referred to and pointed out in the detailed description thereof which follows or will be apparent from such description.

In order that my invention may be more readily understood and its practical advantages more fully appreciated, reference should be had to the accompanying drawing in which I have illustrated one form of mechanical embodiment of my invention, but it will be understood that the same is susceptible of embodiment in other forms of construction than that shown within the scope of the claims.

In the drawing:

Figure 1 is a view in top plan of a sewing machine head and of the driving mechanism for driving and operating the same, such mechanism being shown partly in horizontal section, the table upon which the sewing machine head is supported being partially broken away in order to show the driving mechanism.

Fig. 2 is a view in side elevation showing the manner in which the driving mechanism is driven and operated and indicating that a single driving means may operate a plurality of the said driving mechanisms; and

Fig. 3 is a transverse sectional view taken on the line 3—3 of Fig. 1.

Referring to the drawing:—

1 designates a table top or other similar support for supporting the sewing machine 2 or other machine which may be driven and operated by the operating mechanism. 60 2 designates a pulley provided with a hub 4 which is mounted in a bearing 5 formed by coöperating parts of the twin brackets 6 and 7 which are secured to the underneath side of the table 1 by means of supporting bolts 10. The pulley preferably is provided with flanges 11 forming a groove in which the endless driving belt 12 runs to drive the said pulley.

In Fig. 2 I have indicated a couple of 70 these pulleys 3, but it will be understood that the number may be increased as desired because in practice a number of machines are arranged in a row upon a table and there would be a like number of driving pulleys 75 and associated mechanisms for driving the said machines, all of the said pulleys being preferably driven by a single endless driving belt such as 12.

15 designates a driving friction disk 80 which is secured upon one end of a bar 16 having slidable engagement with the pulley 3 and its hub 4. The said bar is, in the construction shown, connected with the pulley 3 and its hub 4 to rotate therewith by means of a spline pin 17. The disk 15 is adapted to engage the periphery of a friction disk 20, preferably of fiber, which is adjustably secured to a driving shaft 21 mounted in bearings 22 upon the brackets 6 and 7. 90

The shaft 21 is provided with a grooved pulley 25 over which a driving belt 26 operates to drive a pulley 27 secured upon the driving shaft of the sewing machine 2. By means of a coiled spring 30 which is coiled around the outer projecting end of the bar 16, one end of which bears against a flange or collar 31 upon the said bar and the other end of which against the outer end of the hub 4, the bar 16 and the disk 15 secured thereon are held in their outermost positions. When in this position, the disk 15 does not contact with the friction disk 20. As a result the pulley 3 and the disk 15 having operative connection therewith as described may and do rotate, but without effect upon the friction disk 20 and the shaft 21 upon which it is supported.

In order that the bar 16 may be caused to slide through the hub 4 and the pulley 3 110

in opposition to the spring 30 for the purpose of causing the disk 15 to engage the friction disk 20, I have provided a lever 34, pivotally supported intermediate its ends at 35 upon a projection 36 from the bracket 7. One end portion 38 of said lever is in engagement with the outer end of the bar 16, as clearly shown in Fig. 1 of the drawing. The portion of said lever 34 on the opposite side of the pivot 35 is engaged by the upper end 40 of the upwardly extending arm of a bell crank lever 41 which is pivoted at 42. The other arm of said lever extends horizontally and constitutes a foot treadle 43 by means of which the lever 41 may be moved pivotally to operate the lever 34 to effect sliding movements of the bar 16 to effect engagement and disengagement of the disk 15 with and from the friction disk 20.

20 In order to automatically brake the shaft 21 when the disk 15 is disengaged from the friction disk 20, I have provided the outer end portion of the lever 34 with an inwardly extending, projecting portion 45, which, when moved inwardly by the action of the spring 30 moving the end portion 38 thereof outwardly, engages the outer end of a friction rod 46 supported in bearings 47 upon the bracket 7. The inner end of said friction rod is provided with a friction member 50 which is adapted to contact with a brake disk 51 secured upon the shaft 21.

25 A spring 52 interposed between the outer bearing 47 and a laterally extending lug 53 upon the outer end of said friction rod tends to hold the said rod in outer position with the friction member 50 out of contact with the friction disk 51. Consequently when downward pressure is exerted upon the treadle 43 to cause outward swinging movement of the upwardly extending arm of the bell crank 41 to cause outward swinging movement of the end 45 of the lever 34 and inward swinging movement of the end 38 thereof, it is apparent that the spring 52 will cause outward sliding movement of the friction rod 46 to disengage the friction member 50 from the friction disk 51. Simultaneously, the disk 15 is moved 30 into engagement with the friction disk 20 so that the latter is driven, causing rotation of the shaft 21 to drive and operate the machine 2, whether it be a sewing machine or some other character of machine.

35 In the construction shown, the belt 12 is caused by means of the idler rollers 60 to extend partially around the pulleys 3. An idler roller 61 holds one side or span of the belt in spaced relation with respect to the pulleys. The belt 12 is driven by means of a drum or drive wheel 62, preferably motor driven. However, any suitable power may be employed.

40 In order to take up the slack of the belt 12, I have provided an idler pulley 63 sup-

ported upon swinging, weighted, take-up arms 64. The weight is shown at 65.

It is apparent that the spring 30 is stronger than the spring 52 so that when pressure is removed from the treadle 43 the expansive force of the spring 30 causes pivotal movement of the lever 34 in opposition to the spring 52 to cause inward movement of the friction rod 46 to apply the brake 50 and thus quickly stop the operation of the machine.

It will be understood that any other preferred arrangement of the driving belt 12 with respect to the pulleys 3 for driving the latter may be employed.

By adjusting the friction disk 20 along the shaft 21 so that its position with respect to the axis of the driving disk 15 is varied the speed of revolution of the said friction disk and shaft is varied. If the said friction disk should be adjusted to a position beyond the axis of the disk 15 the direction of revolution of said friction disk and shaft 21 would be reversed thereby effecting a reversal in the direction of revolution of the wheel or pulley 27 without crossing or uncrossing the driving belt or cord 26.

I claim:

1. In driving mechanism, in combination, a pulley, means for driving the same, a bar extending axially through the said pulley, said bar being slidable, means for causing rotation of said bar with the said pulley, a shaft, means whereby rotation of said pulley and bar causes rotation of said shaft, means for causing slidable movement of the said bar through said pulley, a brake for controlling rotation of said shaft, and means whereby movement of the last mentioned means operates to control the said brake.

2. In driving mechanism, in combination, a driving disk, means for causing rotation of said disk, a driving shaft, a friction disk mounted on said shaft, a brake disk also mounted on said shaft, means for engaging and disengaging the said driving disk with and from the said friction disk, a brake and means for simultaneously disengaging the same from said brake disk as the driving disk is moved into engagement with the said friction disk and for moving the same into engagement with said brake disk when the said driving disk is moved out of engagement with said friction disk.

3. In driving mechanism, in combination, a driving disk, means for causing rotation of said driving disk, a driving shaft, a friction disk mounted upon said shaft which is adapted to be engaged by the said driving disk, a brake disk also mounted on said driving shaft, means for normally holding the said driving disk out of engagement with the said friction disk, means for moving said driving disk into engagement with

the said friction disk, a brake and means adapted to be actuated by the last mentioned means for applying said brake to said brake disk upon disengagement of the said driving disk from the said friction disk.

4. In driving mechanism, in combination, a pulley, means for causing rotation of said pulley, a bar slidably supported in an axial opening through said pulley, means for causing rotation of said bar with said pulley, a driving disk supported upon the inner end of said bar, a driving shaft, a friction disk supported upon said shaft and adapted to be engaged by the said driving disk, means whereby said friction disk may be adjusted so as to position the same nearer to or farther from the axis of rotation of said driving disk, a brake disk also supported upon said driving shaft, a spring normally holding the said driving disk out of engagement with the said friction disk, a brake adapted to be applied to the said brake disk, a lever pivoted intermediate its ends, means for causing pivotal movement of the said lever, one end of said lever being in engagement with the said bar so that swinging movement of said lever causes sliding movement of said bar to effect engagement and disengagement of the said driving disk with and from the said friction disk, and means intermediate the opposite ends of said lever and the said brake whereby swinging movements of said lever also operate to control the application of said brake to the said brake disk, substantially as described.

5. In driving mechanism, in combination, a plurality of pulleys arranged in series, a driving disk supported upon and driven by each of said pulleys, a plurality of driving shafts, means whereby the said driving shafts are driven from the respective driv-

ing disks, means whereby any one of said driving disks may be operatively disengaged from the said shafts without affecting any one of the other of said shafts, and a common driving means for driving all of said pulleys, substantially as described.

6. In driving mechanism, in combination, a plurality of driven devices arranged in series, a driving disk supported upon and driven by each of said devices, a plurality of driving shafts, means whereby the said driving shafts are driven from the respective driving disks, and a common driving means for driving all of the said driven devices.

7. In driving mechanism, in combination, a plurality of driven devices arranged in series, a driving disk supported upon and driven by each of said devices, a plurality of driving shafts, means whereby the said driving shafts are driven from the said driving disks, means whereby any one of said driving disks may be operatively disconnected from the said shafts without affecting any one of the other said shafts, and a common driving means for driving all of said driven devices.

8. In driving mechanism, in combination, a plurality of pulleys arranged in series, a driving disk supported upon and driven by each of said pulleys, a plurality of driving shafts, means whereby the said driving shafts are driven from the respective driving disks, and an endless driving belt engaging with and driving all of said pulleys.

In testimony that I claim the foregoing as my invention, I have hereunto set my name this 25th day of October, A. D. 1918.

MEYER AXILROD.
